US00D911605S

(12) **United States Design Patent** (10) Patent No.: **US D911,605 S**
Grienay et al. (45) Date of Patent: **** Feb. 23, 2021**

(54) **WATER TANK CHAMBER**(71) Applicant: **CALOR**, Ecully (FR)(72) Inventors: **Arnaud Grienay**, Ecully (FR); **Manon Malatray**, Ecully (FR)(73) Assignee: **CALOR**, Ecully (FR)(***) Term: **15 Years**(21) Appl. No.: **29/665,743**(22) Filed: **Oct. 5, 2018****Related U.S. Application Data**

(63) Continuation of application No. 29/590,200, filed on Jan. 9, 2017, now Pat. No. Des. 864,480.

(30) **Foreign Application Priority Data**

CLAIM

The ornamental design for a water tank chamber, as shown and described.

DESCRIPTION

FIG. 1 is an isometric view of a water tank chamber showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof; and,

FIG. 7 is a bottom view thereof.

The broken lines shown in the figure drawings depict portions of the water tank chamber which form no part of the claimed design.

FIG. 1

FIG. 2

FIG. 3

FIG. 4

FIG. 5

FIG. 6

FIG. 7
